UNITED STATES PATENT OFFICE

PETER B. THORNAS AND EDWARD B. TAYLOR, OF CHICAGO, ILLINOIS, ASSIGNORS TO
E. W. A. ROWLES CO., OF CHICAGO, ILLINOIS, A CORPORATION OF ILLINOIS

WINDOW SHADE FIXTURES

Application filed April 1, 1931. Serial No. 526,870.

This invention relates to certain new and useful improvements in window shade fixtures, and more particularly to means for supporting and cooperating with the type of roller window shades which are positioned in pairs transversely of the window midway the height thereof and adapted to be extended respectively upward and downward to shade desired portions of the window. According to the particular improvements of this invention, the two roller shades of the pair are mounted on a supporting panel which not only serves to prevent the passage of light through the space between the two shades but also is removably mounted on the window frame and is provided with means whereby the entire window shade unit may be removed and hung in a convenient position alongside the window in order to permit free access to the windows for cleaning same or other purposes. Additional shading panels are provided for preventing the passage of light between the ends of adjacent pairs of shades when used on adjacent windows. The improved supporting means also embodies means for easily adjusting the effective length of the shade support.

The principal object of this invention is to provide improvements in window shade fixtures of the type briefly described hereinabove and disclosed more in detail in the specifications which follow.

Another object is to provide improved means for removably supporting window shades transversely of the window.

Another object is to provide improved means for temporarily suspending a window shade unit at one side of the window.

Another object is to provide window shade supporting means of adjustable length.

Another object is to provide improved shielding means for preventing the passage of light between the two shades of a pair or between the ends of adjacent pairs of shades.

Other objects and advantages of this in-

vention will be more apparent from the following detailed description of certain approved forms of devices embodying the principles of this invention.

In the accompanying drawings:

Fig. 1 is a front elevation of a pair of the window shade units mounted on two adjacent windows, parts being broken away, and one of the window shade units being shown in dotted lines and suspended temporarily at one side of the window.

Fig. 2 is a vertical section, taken substantially on the line 2—2 of Fig. 1.

Fig. 3 is a horizontal section on a larger scale, taken substantially on the line 3—3 of Fig. 1.

Fig. 4 is a detached perspective view showing one of the fixed supporting brackets and one of the adjustable end brackets, of the type used in Figs. 1, 2 and 3.

Fig. 5 is an elevation of a window shade unit of the general type shown in Figs. 1, 2 and 3 but using shorter supporting brackets and adapted for use with a single window.

Fig. 6 is a partial horizontal section, taken substantially on the line 6—6 of Fig. 5.

Fig. 7 is a sectional view corresponding to Fig. 6 but showing a different form of supporting bracket.

Fig. 8 is a rear elevation of one end portion of the supporting panel showing the socket by means of which the window shade assembly is suspended when temporarily removed from the window.

Fig. 9 is an upper plan view of the window shade assembly when temporarily suspended at the side of the window.

Fig. 10 is an elevation, partially broken away, showing a simplified form of the invention.

Fig. 11 is a horizontal section taken substantially on the line 11—11 of Fig. 10.

Fig. 12 is a perspective view of the end portion of the shade supporting assembly.

used in the form of the invention disclosed in Figs. 10 and 11.

For the purpose of properly shading long windows, it is often found desirable to use two separate roller shades which are positioned adjacent one another transversely of the window and midway the height thereof, one roller being drawn upwardly and the other downwardly to shade desired portions of the window. Unless these shades are overlapped, there will be a space between the two shades through which light will pass, and to avoid this the pair of shades are sometimes provided with a panel or shield to prevent the passage of light therebetween. According to the present invention the two roller shades are mounted as a unit on this supporting panel, and improved means are provided for supporting this panel either permanently or detachably, from the window frame in a variety of different installations.

To facilitate the disclosure we will first refer to the simplest form of the invention as shown in Figs. 10, 11 and 12, and will then work back to the more detailed forms shown in the other figures. The supporting panel 1 is in the form of a continuous sheet metal plate having rearwardly bent strengthening and stiffening flanges 2 at its upper and lower edges. Adjacent each end of this panel is fixed a shade-supporting bracket 3, the forwardly extending arm of this bracket being formed with an eye 4 and a slot 5 for supporting one of the ends of each of the two roller shades 6. Each bracket 3 is formed with a laterally extending base flange 7 adapted to extend parallel with the front face of panel 1. The end brackets 8 are formed with main plate portions 9 which extend between the front face of panel 1 and the base flanges 7 of the supporting bracket 3, and are also provided with rearwardly extending supporting flanges 10 which are perforated to receive screws 11 by means of which the end brackets are attached directly to the inner faces of the upright window frame members 12. Longitudinally extending slots 13 are formed in the plates 9 of the end brackets 8. The supporting brackets 3 are riveted or bolted directly to the supporting panel 1, the rivets 14 passing through the slots 13 in the end brackets 8. These end brackets are clamped tightly between the panel 1 and base flanges 7 of the shade supporting brackets 3, but the slots 13 permit these end brackets 8 to be driven in or out (longitudinally of the panel 1) to a limited extent so as to vary the distance between the attaching flanges 11 and 60 allow for variation in the distance between the window frame uprights 12. In this manner the effective length of the supporting panel may be easily adjusted, although the panel and shade supporting brackets 3 are permanently and rigidly assembled. It

will be apparent that the panel 1 will prevent the passage of light through the space 15 (Fig. 10) between the upper and lower roller shades 6, as well as act as a fixed supporting means for the pair of shades. 70

The simpler form of window shade assembly shown in Figs. 10, 11 and 12 is adapted to be permanently positioned across the window, but the preferred forms shown in Figs. 1 to 9 are adapted to be readily detachable 75 from the window so as to facilitate washing the windows, or to permit free access to the window for any other purpose. In all forms of the invention here shown, the supporting panel 1 and the shade supporting brackets 3 are of much the same form and secured together in the same manner as already described in connection with Figs. 10, 11 and 12. The end brackets 8 are also adjustably secured in position between the base flanges 7 85 and panel 1 by means of slots 13 through which the rivets are passed, all as described hereinabove. However, the end brackets 8 as shown in Figs. 1 to 9 inclusive are not anchored or attached directly to the window frame, but each bracket 8 is formed at its outer edge with aligned vertical cylindrical eyes 16 similar to hinge lugs and adapted to receive an attaching pin 17. A stationary supporting bracket 18 (see Figs. 1, 2, 3 and 4) 95 is formed at its inner end with a laterally extending flange 19 perforated to receive screws 20 by means of which the brackets 18 are attached to the front face of the window frame uprights 12. At its outer end each bracket 18 100 is formed with a vertically extending cylindrical lug or eye 20 adapted to be received between the eyes 16 of bracket 8, the pin 17 being passed through the aligned eyes 16 and 20 so as to hold the parts together. It will be 105 noted that the brackets 18 as shown in Figs. 1, 2, 3 and 4 are of considerable length so as to space the window shade assemblies a considerable distance in front of the windows. This is necessary with certain types of swing 110 windows, and this feature of the invention will be further referred to hereinafter. In the form shown in Figs. 5 and 6, the stationary brackets 21 are considerably shorter than the brackets 18 previously described, so 115 as to space the window shade assembly closely adjacent the front face of the window frame. Otherwise these brackets 21 are identical with the brackets 18. In the form of the invention shown in Fig. 7, the stationary brackets 22 120 are not provided with the rear laterally extending flanges 19 but are adapted to extend straight to the rear and be secured against the side faces of the window frame uprights 12 as in the form of the invention 125 shown in Figs. 10, 11 and 12.

In any of these forms of the invention it will be apparent that by simply withdrawing the two pins 17 at the two ends of the panel 1, the entire window shade assembly (except 130

for the stationary supporting brackets) can be removed and moved to one side so as to permit free access to the entire window for washing the panes or for other purposes. A 5 socket member is provided on the rear face of the panel 1 adjacent one end thereof (see particularly Figs. 8 and 9), this socket member being conveniently formed by a sheet metal strap member outwardly bowed at its central portion 23 and secured at its ends 24 to the rear face of panel 1. The central portion of the bowed member 23 is notched as indicated at 25. A headed screw 26, or some other similar projection is mounted in or on one 10 portion of the window frame members at a convenient position at one side or the other of the window. When the window shade assembly has been removed from its normal position by withdrawing the two pins 17, the complete 15 assembly is suspended temporarily at one side of the window by hanging the notched socket 23 over the projection 26, all as indicated in Fig. 9 and in dotted lines at the left of Fig. 1.

The form of the invention shown in Figs. 25 1, 2, 3 and 4 is especially adapted for use with windows of the swinging type, especially when two or more such windows are positioned closely adjacent one another with separating mullions. These windows are usually 30 rather deeply inset in the walls, and it is necessary to mount the shades a considerable distance in front of the windows to clear the window handles and permit necessary movements of the windows. For this purpose the long brackets 18 already described are used, and between an adjacent pair of windows a single bracket 27 is mounted on the central mullion 28 to support the adjacent ends of the two adjacent sets of shades. This 35 central bracket 24 will obviously be provided with two separate hinge-eyes 20. It is to be understood that this bracket 27 (as well as the end brackets 18 if desired) can be built up of two or more connected pieces of sheet metal 40 if so desired.

The panels 1 will, as already described, prevent the passage of light between the upper and lower shades of each pair, but, since the shades are set forward a considerable distance in front of the windows, light can pass diagonally from either window through the space 29 (see Fig. 1) between the ends of the adjacent pairs of window shades. In order to close this space, a separate shield member 55 30 is mounted directly behind the shades and spaced forwardly from the central mullion 28. This central panel 30 may be constructed of a single piece of sheet metal or of upper and lower sections, and is supported centrally 60 by the bracket 27 already described, and is supported near its upper and lower ends by auxiliary brackets 31 of any desired form. It will be understood that the upper and lower cross bars of the window frame extend forwardly from the windows beyond the path 65

of vertical travel of the shades, and the central panel 30 will extend vertically between these two cross bars or frame members. In this manner the entire window may be very effectively shaded, or any desired portion thereof may be shaded by manipulating the proper roller shade. Obviously, if more than two adjacent windows are provided, the same construction will be used between each adjacent pair of windows. Any one of the panels 1 and the shades supported thereby may be removed in the manner already described by simply withdrawing the two pins 17 at the ends of the panel. 70 75

Since the central panel or shield 30 is positioned forwardly directly behind the path of vertical travel of the window shades, a depression or pocket 32 is formed in the upper portion of the central panel 30 to permit access to the pins 17 at the adjacent inner ends of the two window shade assemblies. This pocket 32 may be conveniently formed by cutting out a suitable opening in the upper member of the panel 30 and enclosing this by a rearwardly projecting sheet metal housing 33, as best shown in Fig. 3. 80 85

It will be apparent that a set of shades with the supporting panel 1 can be assembled at the factory and shipped in this form, and is adapted for mounting when provided with the type of stationary supporting bracket best adapted for the particular installation. The longitudinal adjustment permitted the end brackets on the panel permit an effective change in the length of the panel, or the distance between the brackets to fit minor variations in the width of the window frames. 90 95 100

We claim:

1. A window shade supporting means comprising a supporting panel adapted to extend transversely of a window, means for rotatably supporting a pair of window shades on the panel, brackets adapted to be mounted on the window frame at opposite sides of the window, means for detachably supporting the ends of the panel from the brackets, and means mounted on the panel and adapted to engage a fixed member for temporarily supporting the panel and parts carried thereby at one side of the window. 105 110 115

2. A window shade supporting means comprising a supporting panel adapted to extend transversely of a window, means for rotatably supporting a pair of window shades on the panel, brackets adapted to be mounted on the window frame at opposite sides of the window, means for detachably supporting the ends of the panel from the brackets, and means mounted on the panel and adapted to engage a fixed member for temporarily hanging the panel and parts carried thereby in upright position at one side of the window. 120 125

3. A window shade supporting means comprising a supporting panel adapted to ex- 130

- tend transversely of a window, means for rotatably supporting a pair of window shades on the panel, brackets adapted to be mounted on the window frame at opposite sides of the window, means for detachably supporting the ends of the panel from the brackets, and a socket member positioned on the rear face of the panel adjacent one end thereof, said socket member being adapted to engage a projection permanently positioned at one side of the window to temporarily hang the panel and parts carried thereby.
4. A window shade supporting means comprising a supporting panel adapted to extend transversely of a window, means for rotatably supporting a pair of window shades on the panel, brackets adapted to be mounted on the window frame at opposite sides of the window, brackets carried by the ends of the panel and adjustable lengthwise thereof to vary the effective length of the panel, said second brackets being detachably connected with the first mentioned brackets to support the panel, and means mounted on the panel and adapted to engage a fixed member for temporarily supporting the panel and parts carried thereby at one side of the window.
5. A window shade supporting means comprising a supporting panel adapted to extend transversely of a window, means for rotatably supporting a pair of window shades on the panel, brackets adapted to be mounted on the window frame at opposite sides of the window, brackets carried by the ends of the panel and adjustable lengthwise thereof to vary the effective length of the panel, said second brackets being detachably connected with the first mentioned brackets to support the panel, and means mounted on the panel and adapted to engage a fixed member for temporarily hanging the panel and parts carried thereby in upright position at one side of the window.
6. A window shade supporting means comprising a supporting panel adapted to extend transversely of a window, means for rotatably supporting a pair of window shades on the panel, brackets adapted to be mounted on the window frame at opposite sides of the window, brackets carried by the ends of the panel and adjustable lengthwise thereof to vary the effective length of the panel, said second brackets being detachably connected with the first mentioned brackets to support the panel, and a socket member positioned on the rear face of the panel adjacent one end thereof, said socket member being adapted to engage a projection permanently positioned at one side of the window to temporarily hang the panel and parts carried thereby.
7. In combination, means for rotatably supporting a window shade transversely of a window, brackets at the sides of the window with which the supporting means is detachably connected, and means for temporarily

supporting the shade and supporting means at one side of the window.

8. In combination, means for rotatably supporting a window shade transversely of a window, brackets at the sides of the window with which the supporting means is detachably connected, and means for temporarily hanging the shade and supporting means in upright position at one side of the window.

9. In combination, means for rotatably supporting a window shade transversely of a window, brackets at the sides of the window with which the supporting means is detachably connected, and a socket means on the supporting member adjacent one end thereof, said socket being adapted to engage a projection permanently positioned at one side of the window to temporarily hang the supporting means and shade.

10. A window shade supporting means comprising a panel adapted to extend transversely of a window, means for rotatably supporting shades on the panel, brackets at the ends of the panel having vertically extending eyes, fixed brackets mounted on the window frame at the sides of the window and having vertical eyes adapted to align with the eyes on the first mentioned brackets, removable pins for connecting the eyes, and means mounted on the panel and adapted to engage a fixed member for temporarily hanging the panel and shades at one side of the window when the pins have been removed.

11. A window shade supporting means comprising a panel adapted to extend transversely of a window, means for rotatably supporting shades on the panel, brackets at the ends of the panel having vertically extending eyes, fixed brackets mounted on the window frame at the sides of the window and having vertical eyes adapted to align with the eyes on the first mentioned brackets, removable pins for connecting the eyes, and a socket member on the panel adapted to engage a fixed projection on the window-frame to hang the panel temporarily at the side of the window when the pins have been removed.

12. A window shade supporting means comprising a panel adapted to extend transversely of a window, brackets fixedly mounted on the panel adjacent the ends thereof for rotatably supporting the shade, and brackets attached to the ends of the panel with capacity for limited adjustment lengthwise thereof for supporting the panel and shade from the window frame.

13. A window shade supporting means comprising a panel adapted to extend transversely of a window, brackets fixedly mounted on the panel adjacent the ends thereof for rotatably supporting the shade, said brackets having forwardly projecting arms in which the shade is mounted and base flanges extending parallel to the face of the panel, end brackets for supporting the panel and

shade from the window frame, said end brackets having portions extending between the panel and base flanges of the first mentioned brackets and provided with slots extending lengthwise of the panel, and rivets secured through the base flanges, the slots of the end brackets, and the end portions of the panel, whereby the first mentioned brackets are permanently secured to the panel, and the end brackets are frictionally secured between the base flanges and panel, but the end brackets are permitted limited adjustment lengthwise of the panel.

14. A window shade supporting means comprising a panel adapted to extend transversely of window, brackets fixedly mounted on the panel adjacent the ends thereof for rotatably supporting the shade, said brackets having forwardly projecting arms in which the shade is mounted and base flanges extending parallel to the face of the panel, end brackets for supporting the panel and shade from the window frame, said end brackets having portions extending between the panel and base flanges of the first mentioned brackets and provided with slots extending lengthwise of the panel, and rivets secured through the base flanges, the slots of the end brackets, and the end portions of the panel, whereby the first mentioned brackets are permanently secured to the panel, and the end brackets are frictionally secured between the base flanges and panel, but the end brackets are permitted limited adjustment lengthwise of the panel, fixed brackets stationarily mounted on the window frame at opposite sides of the window, and means for detachably connecting the end brackets with the fixed brackets.

15. A window shade supporting means comprising a panel adapted to extend transversely of a window, means on the panel adjacent the ends thereof for rotatably supporting the shade, fixed brackets adapted to be anchored on the window frame at opposite sides of the window, and end brackets adapted to be detachably secured to the fixed brackets for supporting the panel and shade, the end brackets being attached to the end portions of the panel with capacity for limited adjustment lengthwise of the panel.

16. A window shade supporting means comprising a panel adapted to extend transversely of a window, means on the panel adjacent the ends thereof for rotatably supporting the shade, fixed brackets adapted to be anchored on the window frame at opposite sides of the window, and end brackets adapted to be detachably secured to the fixed brackets for supporting the panel and shade, the end brackets being clamped between the end portion of the panel and the shade-supporting means and being movable for a limited distance lengthwise of the panel.

17. In combination, means for supporting window shades in position spaced forwardly from a pair of adjacent windows comprising a pair of similar panels for supporting shades transversely of each window, brackets mounted on the window frame at the outer sides of the windows and projecting forwardly for supporting the outer ends of the panels, a bracket projecting forwardly from the central mullion between the windows for supporting the adjacent inner ends of the panels, an upright panel adapted to bridge the space between the shades and prevent the passage of light therebetween, and means for supporting this latter panel from the mullion in forwardly spaced relation therefrom.

18. In combination with means for supporting window shades in position spaced forwardly from a pair of adjacent windows comprising a pair of similar panels for supporting shades transversely of each window, brackets mounted on the window frame at the outer sides of the windows and projecting forwardly for supporting the outer ends of the panels, a bracket projecting forwardly from the central mullion between the windows for supporting the adjacent inner ends of the panels, an upright panel adapted to bridge the space between the shades and prevent the passage of light therebetween, the bracket on the mullion supporting an intermediate portion of the upright panel, and upper and lower brackets mounted on the mullion and supporting the upper and lower end portions of the upright panel.

19. In combination, means for supporting window shades in position spaced forwardly from a pair of adjacent windows comprising a pair of similar panels for supporting shades transversely of each window, brackets mounted on the window frame at the outer sides of the windows and projecting forwardly for supporting the outer ends of the panels, a bracket projecting forwardly from the central mullion between the windows for supporting the adjacent inner ends of the panels, an upright panel adapted to bridge the space between the shades and prevent the passage of light therebetween, means for supporting this latter panel from the mullion in forwardly spaced relation therefrom, and means for detachably supporting the shade-supporting panels from the brackets, the upright panel being provided with a depressed pocket to permit access to the means for attaching the panels to the central bracket.

20. In combination, means for supporting window shades in position spaced forwardly from a pair of adjacent windows comprising a pair of similar panels for supporting shades transversely of each window, brackets mounted on the window frame at the outer sides of the windows and projecting forwardly for supporting the outer ends of the panels, a bracket projecting forwardly from the cen-

tral mullion between the windows for supporting the adjacent inner ends of the panels, an upright panel adapted to bridge the space between the shades and prevent the passage of light therebetween, and means for supporting this latter panel from the mullion in forwardly spaced relation therefrom, means for detachably supporting the shade-supporting panels from the brackets, and means mounted on one of the panels and adapted to engage a fixed member for temporarily supporting the panel and the shades mounted thereon at one side of the window.

CERTIFICATE OF CORRECTION.

Patent No. 1,876,036.

September 6, 1932.

PETER B. THORNAS ET AL.

It is hereby certified that error appears in the printed specification of the above numbered patent requiring correction as follows: Page 3, line 40, for "24" read 27; page 4, lines 65 and 72, claims 7 and 8, respectively, after "means" insert the words mounted on the panel and adapted to engage a fixed member; and that the said Letters Patent should be read with these corrections therein that the same may conform to the record of the case in the Patent Office.

Signed and sealed this 22nd day of November, A. D. 1932.

M. J. Moore,
Acting Commissioner of Patents.
